FOLDING POCKET COMB

William N. Barkwill, New York, N. Y.

Application December 21, 1951, Serial No. 17,802

Term of patent 7 years

(Cl. D86—8)

To all whom it may concern:

Be it known that I, William N. Barkwill, a British subject, residing in New York, county of the Bronx, and State of New York, have invented a new, original, and ornamental Design for a Folding Pocket Comb, of which the following is a specification, reference being had to the accompanying drawing, forming part thereof.

In the drawing,

Fig. 1 is a perspective view of a folding pocket comb, showing my new design.

Fig. 2 is a side view of the comb in open position.

Fig. 3 is a side view of the comb in closed position.

Fig. 4 is a cross sectional view of the comb in closed position.

The essential features of my design reside in the portions shown in full lines.

I claim:

The ornamental design for a folding pocket comb, as shown and described.

WILLIAM N. BARKWILL.
